UNITED STATES PATENT OFFICE.

CHARLES T. DANIEL, OF KANSAS CITY, MISSOURI.

LETTER-FILE, &c.

SPECIFICATION forming part of Letters Patent No. 699,290, dated May 6, 1902.

Application filed January 4, 1902. Serial No. 88,408. (No model.)

To all whom it may concern:

Be it known that I, CHARLES T. DANIEL, a citizen of the United States, residing at Kansas City, in the county of Jackson and State of Missouri, have invented certain new and useful Improvements in Letter-Files, &c.; and I do hereby declare the following to be a full, clear, and exact description of the invention, such as will enable others skilled in the art to 10 which it appertains to make and use the same:

My invention relates to letter-files; and it consists of certain novel features of construction and combination of parts, the preferred form whereof will be fully described in the 15 following specification, reference being had to the accompanying drawings.

The object of my invention is to provide a simple, cheap, and reliably efficient appliance of the character specified by which letters, bill-heads, periodicals, newspapers, and, in fact, all kinds of papers which it is desired 20 to file away for future use and convenient reference may be quickly disposed in convenient packages and secured so that none of 25 them can casually slip out of such package.

A further object of my invention is to enable the letters, bill-heads, &c., to be conveniently filed away from time to time until the desired quantity has been accumulated, 30 when the assembled quantity may be permanently or temporarily bound, as desired.

Other objects and advantages will be hereinafter made clearly apparent.

In the accompanying drawings, Figure 1 is 35 a perspective view of my invention complete, showing an accumulated number of letter-heads in position ready to be permanently bound or secured for future reference. Fig. 2 is a perspective detail of one of the means 40 which I employ to bind the letter-heads, periodicals, or the like after the desired number thereof has been accumulated. Fig. 3 is a perspective detail view showing a portion of the base member of my file, which is provided 45 with a groove adapted to seat the temporary filing-band. Fig. 4 is a perspective detail view showing how the accumulated number of letter-heads may be temporarily bound or secured by means of a cord of the preferred 50 size. Fig. 5 is a perspective detail view of the weight-plate employed by me to temporarily retain the letter-heads, &c., from casu-

ally slipping off of the binding-blades. Fig. 6 is a detail view, on a slightly-reduced scale, showing how the two parts illustrated in Fig. 55 2 are united in order to secure the accumulated number of letter-heads or the like interposed between them. Fig. 7 shows another form of filing-needles, wherein it will be observed that notches are provided in the 60 ends of the needles or blades instead of eyes.

For convenience in referring to the various 65 details of my invention and elements designed to coöperate therewith numerals will be employed, of which—

1 indicates the base portion of my invention, which may be made of any preferred size and of any desired material and is provided near its upper end with a pair of posts 2, having their upper ends curved outwardly 70 and provided with a retaining-head 3, the object of said posts being to extend loosely through suitable apertures provided in a contiguous part of the weight-plate 4, and thus enable said plate by means of its controlling 75 handle 5 to be readily disposed in such position that it will rest upon the letters, bill-heads, or the like, as will be hereinafter more clearly set forth.

Secured in any preferred way to the base-section 1 are the needles 6, which may be made as shown in Fig. 1 or as illustrated in Fig. 7. Each needle is preferably provided with an eye 7 near its upper end, it being understood that each extreme end is properly 85 sharpened, so as to enable it to easily cut its way through a letter or other paper to be filed thereon. If preferred, the said needles may be formed of a single piece of suitable material which is properly bent, so that each 90 of the needles will extend upward through suitable apertures provided in the base-section. It will be understood that the needles are provided with the eyes 7 in order to enable a cord 9 to be employed for the purpose 95 of tying together the accumulated bundle of letter-heads or the like, the disposition of the cord being illustrated in Fig. 4. Each of the needles 6 is preferably provided upon its outer side with the longitudinally-disposed 100 groove 10, while a similar groove may be employed upon the inner side of each needle when the latter are constructed as shown in Fig. 7. When, however, it is desired to

more permanently bind the letters, bill-heads, periodicals, or the like, then I prefer to dispense with the cord and employ a strip of metal, as indicated in Fig. 2, and comprising the middle portion 11, having each end sharpened and bent at right angles, as indicated by the numeral 12. If this metal strip is employed to bind the accumulated number of letters or the like together, then I prefer to provide a suitable groove on the inner side of each needle adapted to snugly receive said ends 12 of said strip, thereby so disposing said ends that they will not obstruct the free downward movement of the letters or the like when the same are filed away from time to time upon the needles 6.

If the metal strip 11 is employed, it is first seated in place, so that the portion 11 will rest directly upon the surface of the base-section 1 between the needles 6, while each angular extension 12 of the metal strip will rest in the groove or slotted opening provided in the needles, and it is therefore obvious that said angular extensions will in no wise impede the free downward movement of the letters as they are filed away. After the desired number of letter-heads or the like has thus been accumulated upon the needles a follower-plate is provided comprising the body portion 13, having at each end a recess 14, the length of the follower-plate being such as to fit snugly between the angular extensions 12, and it is obvious that by bending inwardly the extreme upper ends of said extensions, so that said ends will rest upon a contiguous part of the follower-plate 13, the papers will be permanently and reliably bound together. It is further obvious, however, that any of the letters thus filed and bound will be easily accessible for the purpose of reference, or such individual letter may be bodily removed by bending the points of the angular extensions 12 upward, so as to release the follower-plate 13, as will be readily understood by reference to the drawings.

In Fig. 7 I have shown the needles as differently constructed from those presented in Fig. 1, inasmuch as the eyes 7 have been dispensed with and notches or recesses 7^a employed in lieu thereof. The recesses 7^a and the longitudinal groove 10^a, corresponding to the groove 10 in Fig. 1, have been provided on each side of the needles 6. The cord, therefore, is so disposed that the ends will lie in the recesses or notches 7^a, and the grooves 10^a will thus receive a contiguous part of the cord and present very little obstruction to the free downward movement of the letters as they are filed away. The ends of the cord 6 may therefore be readily grasped and tied together when the desired number of letters or the like has been accumulated.

The manner of using the device illustrated in Fig. 4 it is thought will also be clearly obvious, though it may be stated that if a cord is employed to secure the accumulated number of letters or the like said cord is first

threaded through the eyes of the needles 6 and the middle portion of the cord between the needles disposed in contact with the surface of the body-section 1, thus disposing the needles ready to enable a letter to be forced downward thereon from time to time, it being understood that the weight-plate 4 may be easily brought downward upon each letter by means of the handle 5. The weight-plate 4 is, it will be obvious, designed for the purpose of securing each letter against casual displacement during the filing process, each end of the said plate being provided with an aperture 15, each designed to loosely receive its respective needle. When, however, the desired number of letters or other subject-matter to be treated has been accumulated, the ends of the cord 9 are withdrawn from the needles and tied together, as indicated in dotted lines by numeral 16 in Fig. 4.

It will thus be seen that I have provided means whereby either a metal strip or a cord may be employed to secure the accumulated number of letters and bind them into bundles of desired size for future use, and while I have described the preferred combination and construction of parts I wish to comprehend all substantial equivalents and substitutes that may be considered as falling fairly within the scope of my invention.

Having thus fully described the construction and manner of using my improved letter-file, further reference to the details is deemed unnecessary.

What I claim as new, and desire to secure by Letters Patent, is—

1. The herein-described binding appliance comprising a suitable base-section; a pair of longitudinally-grooved needles carried by said base-section; a weight-plate 4 and means to retain the same in operative combination with said needles; suitable means to hold the accumulated number of letter-heads or the like together, said means being adapted to coöperate with said needles all combined substantially as specified and for the purpose set forth.

2. In a binding appliance of the character specified, a suitable base; needles carried by said base, each needle having a longitudinally-disposed groove on its inner and outer sides as set forth.

3. In a binding appliance, a suitable base; needles carried by said base; each needle being provided upon its inner face with a longitudinal groove, in combination with a binder-plate 11 having right-angled extensions 12, each of said extensions being designed to be received by the groove in one of said needles, and a follower-plate having a recess in each end adapted to fit between said needles and said extensions whereby when said extensions are bent downward upon the follower-plate the papers will be securely bound together all combined substantially as specified and for the purpose set forth.

4. The herein-described binder comprising

a base-section; needles carried by one end thereof, each needle having a longitudinal groove, in combination with a suitable paper-engaging device adapted to coöperate with said needles; a post having outwardly-curved terminals adjacent to each needle, and a weight-plate fitting on said posts and provided upon its inner edge with apertures adapted to receive said needles, whereby said weight-plate may be freely moved downward

upon the needles or elevated out of the way upon the curved terminals of said posts as and for the purpose set forth.

In testimony whereof I affix my signature in presence of two witnesses.

CHARLES T. DANIEL.
